(57) **CLAIM**

The ornamental design for a jacket for portable terminal, as shown and described.

DESCRIPTION

FIG. 1 is a front, right side and top perspective view of a jacket for portable terminal in accordance with a first embodiment of our new design;

FIG. 2 is a front elevation view of the jacket for portable terminal in accordance with the first embodiment of our new design;

FIG. 3 is a rear elevation view of the jacket for portable terminal in accordance with the first embodiment of our new design;

FIG. 4 is a left side view of the jacket for portable terminal in accordance with the first embodiment of our new design;

FIG. 5 is a right side view of the jacket for portable terminal in accordance with the first embodiment of our new design;

FIG. 6 is a top plan view of the jacket for portable terminal in accordance with the first embodiment of our new design;

FIG. 7 is a bottom plan view of the jacket for portable terminal in accordance with the first embodiment of our new design;

FIG. 8 is a front, right side and top perspective view of a jacket for portable terminal in accordance with a second embodiment of our new design;

FIG. 9 is a front elevation view of the jacket for portable terminal in accordance with the second embodiment of our new design;

FIG. 10 is a rear elevation view of the jacket for portable terminal in accordance with the second embodiment of our new design;

FIG. 11 is a left side view of the jacket for portable terminal in accordance with the second embodiment of our new design;

FIG. 12 is a right side view of the jacket for portable terminal in accordance with the second embodiment of our new design;

FIG. 13 is a top plan view of the jacket for portable terminal in accordance with the second embodiment of our new design; and,

FIG. 14 is a bottom plan view of the jacket for portable terminal in accordance with the second embodiment of our new design.
